UNITED STATES PATENT OFFICE

GEORGE RECHTER, OF SAN FRANCISCO, CALIFORNIA

HORN BLOWING ATTACHMENT FOR STEERING WHEELS

Application filed November 7, 1929. Serial No. 405,448.

The invention aims to provide a new and improved attachment for the steering wheels of motor vehicles, of such nature as to permit depression of the conventional horn button, without the necessity of the driver releasing his grip upon the rim of the wheel, being particularly advantageous when only one hand is free for steering, the other being then required for shifting gears or for some other duty.

With the foregoing in view, the invention resides in the novel subject matter herein-after described and claimed, description being accomplished by reference to the accompanying drawings.

Fig. 1 is a sectional perspective view with parts omitted.

Fig. 2 is an enlarged vertical sectional view.

Fig. 3 is a detail vertical section showing a modified form of construction.

Fig. 4 is a detail top plan view showing another variation of construction.

Fig. 5 is a small top plan view of the entire frame of the attachment.

The preferred construction has been illustrated and while such construction will be herein specifically explained, it is to be understood that within the scope of the invention as claimed, numerous variations may be made.

The numeral 6 denotes a flat ring to surround the conventional horn button B at the center of a steering wheel W. Radiating from this ring and secured thereto in any preferred manner, are a plurality of arms 7 for disposition over the wheel spokes S, said arms being of flat strip form and having their outer ends downwardly offset from their inner ends, providing vertical portions 8 between said inner and outer ends. The outer ends of the arms 7 are secured upon the spokes S, being preferably provided with spoke straddling ears 9 through which clamping bolts 10 pass, said bolts being adapted to underlie the spokes. This construction and that hereinafter described, is duplicated in connection with each arm 7 but for purposes of illustration, details of only one unit of the

description may be conveniently placed in singular number.

The inner and outer portions of the arm 7 are provided with substantially flat, sleeve-like guides 11 and 11^a respectively, which may well be formed by bending flanges, as shown. A slide strip 12 is slidably engaged with these guides, the inner and outer end portions of said slide strip being offset vertically, providing a vertical portion 13 between the ends of said strip and normally spaced outwardly from the vertical portion 8 of the strip or arm 7. Between these vertical portions 8 and 13, a coiled spring 14 is confined, said spring being suitably connected with said portions and acting to normally force the strip 12 outwardly toward the rim of the wheel W. The inner end of this strip is provided with a vertically yieldable terminal 15 carrying a shoe 16 which is preferably in the form of a roller. This shoe normally rests upon a portion of the arm 7 or the contiguous portion of the ring 6, the equivalent of a track being thus provided, upon which the shoe is movable. The outer end of strip 12 is provided with a handle 17 near the rim of the wheel, and by inwardly moving this handle, the strip is slid to move the shoe 16 from the ring 6 onto the horn button B. As soon as shoe 16 leaves ring 6, it is depressed under the inherent resiliency of the terminal 15, with the result that it depresses the button B and sounds the horn. As soon as handle 17 is released, spring 14 restores the slide strip 12 to its normal position and incident to such restoration, the shoe 16 again moves onto the upper side of the ring 6, in readiness to again act.

For adapting the invention to use with steering wheels in which the horn button is an unusual distance above the wheel hub, due for instance to the location of gas and spark controls over said hub, the construction illustrated in Fig. 3 may be followed. In this view, the inner and outer portions of the secured strip or arm 7^a and the corresponding portions of the slidable strip 12^a, are formed of two sections having vertically slidable overlapped portions 8^a and 13^a re-

spectively, which are adjustably connected with each other by any desired means, such as the clamping bolts 18 passing through slots 19. This construction allows the inner 5 end portions of the strips 7^a and 12^a to be set at any required distance above the other end portions of said strips.

Fig. 4 discloses another variation of construction, in which a slide strip 12^b is shown, 10 said strip being provided at its inner end with a notch 20 receiving a portion of a roller or shoe 16^a, said roller or shoe being mounted upon a pivoted yoke 21 whose pivot 22 connects it with said strip 12^b. A coiled torsion spring 23 is disposed around the pivot 22 with one of its ends engaged with the strip 12^b and its other end engaged with the yoke 21. This construction affords a vertically 15 yieldable terminal for the strip 12^b, which terminal will be depressed by the spring 23 to correspondingly depress the roller 16^a and the horn button, in the same manner as the spring terminal 15 above described depresses the roller 6 and the button. 20

Excellent results are obtainable from the details disclosed and while they are preferably followed as above stated, attention is again invited to the fact that within the 30 scope of the invention as claimed, variations may be made.

I claim:—

1. A horn blowing attachment for a steering wheel, comprising a strip, means for securing said strip upon a spoke of the wheel, 35 guides carried by the inner and outer end portions of said strip, a second strip slidably engaged with said guides, a shoe on the inner end of said second strip adapted to bear 40 against and depress the conventional horn button upon inward sliding of said second strip, a handle at the outer end of said second strip for inwardly sliding the same, and a spring for returning said second strip after 45 each operation thereof.

2. A structure as specified in claim 1; the outer ends of both strips being downwardly offset from the inner ends thereof providing vertical portions between the ends of said 50 strips, said spring being confined between said vertical portions.

3. A structure as specified in claim 1; said shoe normally resting upon said secured strip but being movable therefrom onto the horn 55 button, said second strip having a yieldable downwardly biased terminal carrying said shoe and adapted to depress the latter when it is moved from said secured strip.

4. A horn blowing attachment for a steering wheel, comprising an upwardly facing track and means for mounting it on the wheel at the periphery of the conventional horn button and substantially even with the upper surface of the latter, a shoe and means 60 mounting it in engagement with the upper

side of said track in position for movement entirely off of said track onto the horn button, and means for depressing said shoe to depress the button when said shoe is moved off of said track onto said button. 70

5. A horn blowing attachment for a steering wheel, comprising an upwardly facing track and means for mounting it on the wheel at the periphery of the conventional horn button and substantially even with the upper surface of the latter, a shoe engaged with the upper side of said track and movable entirely off of said track onto the horn button, and a slide having a yieldable terminal carrying said shoe, said terminal being downwardly-biased and adapted to depress said shoe to depress the button when the shoe is moved off of the track onto said button. 75

6. A horn blowing attachment for a steering wheel, comprising a ring to surround the conventional horn button, arms projecting radially outward from said ring to overlie the wheel spokes, means for fixedly securing said arms to said spokes, and button-depressing means slidably mounted on said arms for movement longitudinally of the latter. 80

7. A structure as specified in claim 6; said securing means comprising spoke-straddling ears integral with said arms, and bolts passing through said ears to underlie the spokes. 85

In testimony whereof I have hereunto affixed my signature.

GEORGE RECHTER.
